UNITED STATES PATENT OFFICE

126,409

DESIGN FOR A SOCKET HEAD CAP SCREW

Charles S. Trott, New York, N. Y., assignor to
Parker-Kalon Corporation, New York, N. Y., a
corporation of New York

Application January 4, 1941, Serial No. 97,804

Term of patent 14 years

To all whom it may concern:

Be it known that I, Charles S. Trott, a citizen of the United States, residing at New York, in the county of New York and State of New York, have invented a new, original, and ornamental Design for a Socket Head Cap Screw, of which the following is a specification, reference being had to the accompanying drawing, forming part thereof.

Figure 1 is a view in side elevation of a socket head cap screw embodying my new design; and
Figure 2 is a top plan view thereof.

I claim:

The ornamental design for a socket head cap screw, as shown.

CHARLES S. TROTT.
